UNITED STATES PATENT OFFICE

THOMAS H. GRAY, OF FORT WORTH, TEXAS

DESIGN FOR A HOT WATER BOTTLE

Application filed October 5, 1931. Serial No. 41,303. Term of patent 14 years.

To all whom it may concern:

Be it known that I, THOMAS H. GRAY, a citizen of the United States, residing at Fort Worth, in the county of Tarrant and State of Texas, have invented a new, original, and ornamental Design for a Hot Water Bottle, of which the following is a specification, reference being had to the accompanying drawings, forming part thereof.

Figure 1 is a front elevational view of a hot water bottle showing my new design, and

Figure 2 is a side elevational view.

I claim:

The ornamental design for a hot water bottle, substantially as shown.

THOMAS H. GRAY.
